UNITED STATES PATENT OFFICE.

ALBERT E. GRAHAM, OF WINDSOR, CONNECTICUT.

WINDOW-SASH CATCH.

SPECIFICATION forming part of Letters Patent No. 542,050, dated July 2, 1895.

Application filed May 17, 1895. Serial No. 549,646. (No model.)

To all whom it may concern:

Be it known that I, ALBERT E. GRAHAM, a citizen of the United States, residing at Windsor, in the county of Hartford and State 5 of Connecticut, have invented certain new and useful Improvements in Window-Sash Catches, of which the following is a specification.

The invention relates more particularly to 10 those catches that are employed for retaining and securing window-sash which are not provided with counterbalancing-weights; and the object of the invention is to provide a simple, cheap, and convenient device applicable to 15 window-sash of this class which can be instantly set, so that the sash may be raised easily and made to stay at the desired location, which can be turned so that the sash can be readily lowered, and which can be so arranged as to lock the sash either open or 20 closed.

Referring to the accompanying drawings, Figure 1 is a plan of the device. Fig. 2 is a horizontal section of the device shown as embedded in the window-sash, as in use; and Fig. 25 3 is a vertical section of the same.

In the views 1 indicates one of the vertical side pieces of a window-frame, and 2 indicates a portion of a sash that is adapted to be 30 moved up and down the frame. Along the runway for the sash is secured a curved strip 3, and the edge of the sash is grooved or mortised so as to slide up and down this strip.

The catch has a face-plate 4 that is adapted 35 to be set into the edge of the sash and fit around the strip 3, and projecting inward from this plate is a hub 5. Within a socket in the face-plate is a hollow block 6, which has a tubular stem 7. This block is normally 40 thrust outward from the socket in the face-plate by means of a spring 8 that thrusts between a shoulder 9 on the interior of the hub of the face-plate and a shoulder 10 formed on the exterior of the stem of this block. Passing 45 through the opening in this block and its stem is a spring bolt or plunger 11. This bolt is adapted to be forced outward by means of a spring 12 that thrusts between a shoulder 13 in the interior of the stem of the block and

a shoulder 14 on the exterior of the bolt. This 50 bolt is provided with a handle 15 by which it may be pulled inward against the thrust of the spring 12.

A pin 16 projects from this bolt through a slot in the stem of the block and a slot in the 55 hub of the face-plate. These slots are so shaped that when the bolt is drawn backward by means of the handle and the bolt is given a part of a revolution so the pin moves onto the middle step 17 of the slot, the end of the 60 bolt and the end of the block are flush, but both project outward slightly from the line of the face-plate, and when the bolt is pulled inward and turned so that the pin will rest upon the highest step 18 of the slot in the hub of 65 the face-plate, both the bolt and the block will be drawn within the socket in the face-plate so that they will be flush with the face-plate. The strip that is put on the runway is provided with ratchet-teeth 19 and with locking 70 perforations 20.

When the bolt is drawn inward and turned so that the pin rests on the highest step of the slot through the hub of the face-plate, the sash can be freely raised up or lowered down, for then both the block and the 75 bolt are flush with the face-plate. When the bolt is drawn in and the pin rests on the middle step of the slot, then the window can be raised but cannot be lowered, for the block acts as a spring-ratchet against the teeth and 80 is forced inward as the sash is raised up but springs outward when a tooth is passed, so that the sash cannot be then let down. When the bolt is let out so that the pin rests in the lowest step of the slot through the hub of the plate, 85 the bolt projects outward beyond the end of the block in such manner that it will project into one of the openings 20 made in the strip and thus lock the window against further movement. 90

The device is simple, cheap, and can be made very small, so that it may be set into the sash of any ordinary window of that class which does not have counterbalancing-weights. When such a window is provided 95 with this device and it desired to raise the window, the bolt is pulled out and the pin is turned, so as to rest in the middle step of the

slot, and then the window can be raised and will stay at any elevation.

The device is easily set, so that the window may be lowered at any time; and it is also so constructed that the window may be locked very quickly at any desired point.

I claim as my invention—

1. In a window sash catch, in combination, a shell adapted to be inserted in the sash, a spring block movable within the shell, and a spring bolt movable within the block, substantially as specified.

2. In a window sash catch, in combination, a shell adapted to be inserted in the sash, a spring block movable within the shell, a spring bolt movable within the block, and a pin and slot connection between the bolt and the block

whereby the bolt moves independently of the block for a portion of its inward movement only, substantially as specified.

3. In a window sash catch, in combination, a shell consisting of a face plate and a hub adapted to be inserted in the edge of a sash, a spring block with a tubular stem movable within the shell, a spring bolt movable within the stem of the block and having a handle, and a pin projecting from the bolt through slots in the stem of the block and in the hub of the shell, substantially as specified.

ALBERT E. GRAHAM.
